UNITED STATES PATENT OFFICE.

FRANK SEPTIMUS DEVONTEAUX SCOTT, OF LONDON, ENGLAND.

APPARATUS FOR ASSORTING AND COUNTING COINS.

SPECIFICATION forming part of Letters Patent No. 634,506, dated October 10, 1899.

Application filed December 6, 1897. Serial No. 660,998. (No model.)

To all whom it may concern:

Be it known that I, FRANK SEPTIMUS DEVONTEAUX SCOTT, a subject of the Queen of Great Britain and Ireland, and a resident of 5 25 Upper Bedford Place, London, England, have invented certain new and useful Improvements in Apparatus for Assorting and Calculating Coins, of which the following is a specification.

10 The object of my invention is to provide an apparatus that is capable of quickly assorting and also calculating the total amount of a quantity of coins placed indiscriminately into it.

15 In the accompanying sheet of drawings, Figure 1 is a front elevation of the apparatus with the case in section. Fig. 2 is a cross-section through *a a*, Fig. 1, showing also a portion of the calculating mechanism through 20 *xx*. Fig. 3 is a plan, partly in section, of a fragment of the coin-assorting device. Fig. 4 is a full-size plan of one set of the calculating mechanism. Fig. 5 is a side view of same. Figs. 6 and 7 show the arrangement of the 25 striking-arms. Fig. 8 is an alternative detail in connection with the calculating mechanism.

In carrying out the invention I form a suitably-shaped case or frame A, in the top of 30 which is an opening B, through which the coins are fed into the hopper C. A chute C', forming a part of this hopper, is inclined toward a band-elevator D, mounted upon rollers D' and D'' and having a number of ridges, such as D³, a suitable distance apart formed 35 upon its external surface, so that the coins which have been placed into said hopper can be picked up singly on their edge and carried to the assorter or separator E. Said separator consists of one or more inclined rails similar 40 to F and F', fastened to a partition F², which is inclined slightly backward and provided with diverting-strips F³ for causing the coins to be turned off said rail, according to their size and denomination. The portion G of the 45 inclined rail F is reduced in thickness, so that should two coins happen to get on the rail side by side the outside coin will fall off said rail at the reduced part and drop either onto the rail F', which has a similar reduced part 50 at H, or onto a conveyer I, having ridges on its external surface. When only one rail is used, this conveyer is arranged under said re-

duced portion to convey the coins which fall off the rail back into the hopper by depositing them in the inclined slot I'; but should two 55 or more rails be used the conveyer extends from the lowest rail.

A guide-piece J, connected with the bar J', is pressed lightly against the partition F² by a suitable spring in order to direct the coins 60 onto the rail F as they fall from the elevator. Another guide-piece K is used to direct the coins which fall off the upper rail onto the lower one.

A hinged flap L, which has its free end resting on the elevator, may be used to minimize the liability of two coins side by side passing from said elevator onto the rail F.

Receptacles M are arranged beneath the assorter and correspond in number to the coins 70 to be separated, so that each denomination of coin has its particular receptacle. Each of these receptacles is provided with a separate sliding bar N, which communicates with the bottom of the receptacle and is capable of 75 pushing the bottom coin in said receptacle through a slot O, formed opposite the sliding bar.

A horizontal shaft P is arranged above the sliding bars N and is provided with a suitable 80 number of striking-arms Q, Figs. 6 and 7, which engage said sliding bars in succession and cause them to be moved forward the required distance, after which said bars are drawn back to their original position by 85 springs R or forced back by the arms S, Fig. 8, placed in a suitable position upon a shaft and actuated by toothed or other gearing connected with the shaft P, carrying the striking-arms.

A sliding lever T, Figs. 4 and 5, is hinged to the arm T' of each sliding bar N and has a pin T² projected downward from the extension T³ of said lever capable of engaging the carrier U for the pawl V, which operates 95 in a slot U' and actuates the ratchet-wheel W. The carriers U slide in suitable slots U' of the frame, which vary in length to correspond with the value of the coins, Fig. 6, and springs U² are connected to the carriers to 100 retract them when the sliding bars are withdrawn. There are as many of said ratchet-wheels and component parts as there are receptacles for the different denominations of

coins. All of these ratchet-wheels W are arranged upon the spindle W' , carrying the main registering wheel W^2 , which communicates with other suitable multiplying mechanism, so that any quantity of coins can be calculated.

The sliding levers T before mentioned are capable of being moved laterally by pivoted dogs similar to X , Fig. 4, arranged at one side of the slots O and which are forced back by the coins as they are ejected by the sliding bars N , so that while there are coins in the receptacles M and the sliding bars are operated the said levers are forced outward by the dogs X and the pins T^2 are caused to engage the carriers U for the pawls V , which actuate the ratchet-wheels W ; but should there be no coins in said receptacles and the sliding bars operated the levers T travel parallel with the sliding bars and the pins T^2 pass by the carriers U , and therefore do not cause any movement to the ratchet-wheels. Each of said levers is kept in contact with its relative dog X by a suitable spring Y , and is also retained in the proper position by a guide Y' , Fig. 4. The stop Y^2 is secured at the side of the slots O to prevent the coins as they are ejected from being forced on one side by the device X .

The apparatus shown in the drawings is constructed for assorting and calculating five different denominations of coins—that is to say, nickels, dimes, quarters, half-dollars, and dollars; but it will be understood that it can be made for any number of coins from the least to the greatest in value.

The manner of registering the different values of the coins is as follows: Suppose there is one coin in each of the receptacles M . Then as the shaft P is rotated the first striking-arm Q causes the bar N for the five-cents receptacle to slide forward and push the coin at the same time the lever T is carried forward, and the coin passing through the slot forces the device X back, and consequently moves the lever T outward, so that the pin T^2 will engage the carrier U and push it a sufficient distance in its slot U' for the pawl V to turn the ratchet-wheel one tooth, which indicates five cents on the registering-wheel. The next striking-arm then comes into operation and pushes the sliding bar forward to eject the ten cents from its receptacle. In this case the said pin T^2 pushes the carrier U for the pawl V forward a sufficient distance to turn the ratchet-wheel two teeth and records a total of fifteen cents, after which the third striking-arm comes into operation, and the ratchet-wheel for the twenty-five cents is turned five teeth more, for the half-dollar it is turned ten teeth, and a dollar twenty teeth, thus recording altogether a total of one dollar ninety cents. The length of each pawl and the distance it travels are in proportion to the denomination of coin to which it relates. After the coins have been ejected by the sliding bars they fall either

into tubes Z , corresponding to their size, arranged in front of the apparatus, or into a tray having divisions for the various coins.

Suitable gearing, operated by a turning handle Z' or other device, is arranged at one end of the apparatus to impart movement to the elevator D , conveyer I , and also the horizontal shaft P , so that by simply turning this handle or setting the gearing in motion the coins placed in the hopper are assorted and calculated.

Having now described my invention, what I claim as new, and desire to secure by Letters Patent, is—

1. In a device of the character described, a hopper, means for conveying coins therefrom, an assorter adapted to receive the coins from the conveying means and provided with inclined rails on which the coins roll, said rails having reduced portions permitting but one coin to pass at a time, a guide-piece directing the coins dropped by one rail to the other rail, and a conveyer for returning the disengaged coins to the hopper, substantially as described.

2. In a device of the character described, a hopper, an assorter comprising a slanting partition with inclined rails thereon, an elevator for conveying coins from the hopper to the assorter, guide-pieces located above the rails to direct the coins thereto, and means for returning the disengaged coins to the hopper, substantially as described.

3. In a device of the character described, a hopper, an assorter comprising a slanting partition with a pair of inclined rails thereon, one located above the other, an elevator adapted to convey coins from the hopper to the assorter, guide-pieces over the rails to direct the coins thereto, each of said rails being provided with a reduced portion permitting but one coin to pass at a time, the reduced portion of the upper rail being out of vertical alignment with that of the lower rail to drop its surplus coins on the wide portion of the lower rail where they then pass onto the reduced portion thereof, and a conveyer to return the coins not engaged by either rail to an inclined slot leading to the hopper, substantially as described.

4. In a device of the character described, a receptacle for disks having a slot in its lower end, a sliding bar adapted to discharge the contents of the receptacle through the slot, a dog located in the path of the disks so as to be moved thereby when being ejected, a lever carried by the sliding bar and operated by the dog, a registering means located in the path of the lever to be engaged thereby when operated by the dog, but being so spaced from the lever as to be passed thereby without engagement when no disk is being ejected, substantially as described.

5. In a device of the character described, a receptacle for disks having a slot in its lower end, a sliding bar adapted to discharge the contents of the receptacle through the slot,

- a pivoted dog located in the path of the disks so as to be swung thereby when being ejected, a spring-pressed lever pivoted to the sliding bar and bearing on the dog, an indicating means, and a pin projecting from the lever adapted to engage the indicating means when the lever is swung by the dog but to pass clear thereof when no disk is being ejected, substantially as described.
- 10 6. In a device of the character described, a frame, receptacles for coins secured thereon and provided with slots in their lower ends, sliding bars adapted to discharge the contents of the receptacles through said slots, pivoted dogs located in the paths of the coins so as to be swung thereby when being ejected, spring-pressed levers pivoted to the sliding bars and bearing on the dogs, pins depending from the levers, carriers slidable in slots of the frame 15 and so located as to be engaged by the pins only when their levers are swung by the dogs, pawls pivoted to the carriers, ratchet-wheels engaged by the pawls, and means for operat-

ing the sliding bars successively, substantially as described. 25

7. In a device of the character described, a series of receptacles for coins of different values, sliding bars adapted to discharge the contents of the receptacles through suitable slots in the lower ends thereof, dogs located in the paths of the coins to be moved thereby when being ejected, levers pivoted to the sliding bars and operated by the dogs, carriers so located as to be engaged by the levers only when operated by the dogs, said carriers being slideable for distances varying from each other corresponding to the relative value of the coins they represent, and indicating means operated by the carriers, as and for the purpose described. 30

In witness whereof I have hereunto set my hand in the presence of two witnesses.
